Primary Examiner—Holly H Bayham(74) *Attorney, Agent, or Firm*—Fredrikson & Byron, P.A.(57) **CLAIM**

I claim the ornamental design for a handbag, as shown and described.

DESCRIPTION

FIG. 1 is a front elevation view of my new design for a handbag, the rear elevation view being a mirror image of the front elevation view shown;

FIG. 2 is a right side elevation view of the handbag, the left side elevation view being a mirror image of the right side elevation view shown;

FIG. 3 is a top plan view of the handbag;

FIG. 4 is a right side elevation view of the handbag, wherein front and rear side panels of the design are open;

FIG. 5 is a top plan view of the handbag, wherein the front and rear side panels are open; and,

FIG. 6 is a front elevational view of the handbag, wherein the front side panel is open with the rear elevation view wherein the side panel is open is a mirror image of the front elevation view shown.

Portions of the article that are not shown in the drawings form no part of the claimed design. Broken lines shown in each of the drawings represent environmental structures that form no part of the claimed design.
